AMMUNITION

Marcus W. Haines, Long Beach, Calif., assignor,
by mesne assignments, of one-half to The
Technicraft Engineering Corporation, Los An-
geles, Calif., a corporation of California

Application November 12, 1932, Serial No. 642,407

6 Claims. (Cl. 102—12)

The present invention is an improvement in ammunition and relates to a type of projectile for use in underground or underwater firing.

While the structure hereinafter described is particularly well adapted for use in association with perforating guns lowered into deep wells for the purpose of puncturing well casings or the like, and while several of the novel features described and claimed herein are the direct result of experimental work and design in that field, the usefulness of the invention is by no means limited thereto and affects, generally, many types of ammunition, guns and projectiles.

The objects of my invention include:

15 The provision, in a percussive device, of means, co-acting with a projectile and its firing chamber, for retarding the expansive force of an explosive charge, used to start said projectile, in a manner adapted to utilize, as nearly as possible, the maximum energy of said charge in the propulsion of said projectile.

20 The provision of a means for increasing the muzzle velocity of a projectile, with the use of a given charge of explosive, said means also serving as a fluid tight seal before firing.

25 And the provision of a positive means for withstanding external pressure, such as hydrostatic pressure encountered at great depths, as in the case of oil well casings.

30 The structure hereinafter described was evolved to correct, or rather to supplant other devices which proved inoperative or ineffectual in deep well work.

Such ammunition as was available for such use proved useless principally for two reasons:— First, a lack of penetrating force sufficient to accomplish the perforation of well casing and surrounding formation; second, when a type of ammunition was found which would accomplish, 40 reasonably well, the result desired, when demonstrated at or near the surface of the ground, said ammunition failed entirely at great depths, because of the fact that external hydrostatic pressure on the exposed end of the projectile forced said projectile into its shell and damped the firing charge, causing misfire.

45 These objectionable features are met and remedied by my improved ammunition.

Other objects and advantages will become apparent as this description proceeds.

In the accompanying drawing Figure 1 is a longitudinal central cross sectional view of a removable barrel, here shown as engaged with a fragment of gun carriage or body, and in said barrel, also in cross section, a shell, explosive

charge, projectile and fire retarding means embodying my invention.

Figures 2 and 3 are end views of the barrel shown in Figure 1, and

Figure 4 is a full face view of a gasket member. 5

Referring to the drawing the numeral 1 indicates, in its entirety, a barrel member, here shown as cylindrical, which is threaded externally at 2, for engagement with a bored and tapped member 3 which may be either a part of a breech mechanism or may be a hull or casing of a submarine implement.

The threads 2 serve a dual purpose, serving as a means for tightening a fluid seal to be later described.

15 Bores 4 in the muzzle end of barrel 1 afford means for engagement of the barrel by a spanner wrench, in a well known manner.

Barrel 1 is centrally bored, and said bore is successively reduced in diameter as indicated at 20 6, 7 and 8, to form, respectively, a shell base chamber, a cartridge chamber, and a barrel chamber for a projectile 9.

The diameter of the barrel chamber 8 coincides with the maximum diameter of the projectile 9. 25

When the barrel 1 is to be loaded a cartridge 11 is inserted in chamber 7 and said barrel is threaded into the breech 3 until the base 12 of said cartridge abuts said breech and a detonating cap 13 registers with a firing pin 14, normally held from contact with said cap by a spring 16 one end of which bears against a head 17 of said pin and the opposite end against the bottom of a bore 18 into which said head is slidable. 30

When said pin 14 is driven the cap 13 ignites a charge of explosive 19 within said cartridge 11 and expels the projectile 9 through bore 8.

35 Projectile 9 consists of a metal jacket or bullet of steel or suitable alloy provided with a core base 20 of relatively softer metal of a malleable nature adapted to expand under pressure and protect the explosive charge 19 from intrusion of liquid in which the barrel 1 is immersed.

This seal is augmented by a shoulder 21 in the 40 cartridge shell 11 and by use of a washer or gasket 22, shown in Figs. 1 and 4.

45 Gasket 22 is here shown as circular in form and adapted to seat in an annular groove 23 in the projectile 9, being either formed therein or force 50 fitted into said groove.

Any suitable alloy or compound may be used for the gasket which will best suit the conditions of use for which it is intended.

The washer or gasket serves a dual purpose. 55

It serves to seal the combustible charge 19 within cartridge 11 and acts as a stop when barrel 1 is threaded into breech-block 3.

A shoulder 24 (bottom of bore 7) encounters said gasket which is rigidly held against movement by contact of shell base 12 with the breech 3.

When so engaged gasket 22 also serves as a retarding means to delay the start of the projectile 11.

It is a well known fact that a very considerable part of the energy of an explosive charge, of the type shown herein, is dissipated during the initial stage of combustion and that muzzle velocity, and, consequently, the degree of penetration of a projectile, is determined by certain recognized principles which influence the manufacture of munitions.

I have discovered that I can increase, very materially, the penetrative effectiveness of a projectile by seating the gasket 22 in the peripheral groove 23 with the advancing face of said gasket in contact with the shoulder 24 of the barrel 1.

25 When the charge 19 is fired gasket 22 shears on the dotted line A of Figure 4, said line representing the circumference of bore 8, and the outer portion remains in chamber 7 to be later removed with the empty shell 9.

30 The innermost portion of the sheared ring leaves the barrel 1 through bore 8 with the projectile 11.

Obviously various characteristics can be imparted to said gasket, either by choice of metals or alloys or by changes in physical dimensions, during its manufacture, and the degree of resistance which it offers to shearing force can be determined by experiment until a form and material are found best suited to the uses for which it is to be employed.

I claim:—

1. A cartridge assembly for use in a well casting perforator having a body and a barrel member screwthreaded into said body and provided with a stepped bore with the largest bore at the rear, the stepped portion of the bore providing a shoulder adjacent the muzzle; said assembly comprising a cartridge case in said largest bore, a propellant fuel within said cartridge and means to ignite the same, a projectile in said cartridge provided with an annular groove, a frangible sealing and retarding gasket within said groove and cooperating with said shoulder when the barrel is threaded into the body to seal the cartridge chamber against the entrance of fluid and to retard the forward movement of the projectile when the cartridge is discharged.

2. The combination with a barrel member having a bore in which is formed a shoulder adjacent the muzzle of the barrel member, of a cartridge assembly comprising, a cartridge case, a propellant fuel therein, means for igniting the fuel, a projectile for said cartridge case, and a frangible sealing and retarding gasket secured around the forward portion of the projectile and engageable with said shoulder in fluid sealing relation therewith, and further engageable to delay discharge of the projectile upon igniting the fuel.

3. The combination with a barrel member having a bore in which is formed a shoulder adjacent the muzzle of the barrel member, of a cartridge assembly comprising, a cartridge case, a propellant fuel therein, means for igniting the fuel, a projectile for said cartridge case, and a frangible means engageable with said shoulder and the forward end of said projectile to form a sealing and securing connection between the projectile and barrel member operative to seal during initial travel of the projectile.

4. The combination with a barrel member having a bore in which is formed a shoulder adjacent the muzzle of the barrel member, and an explosive cartridge means, of a projectile mounted within the barrel member and co-actively associated with the cartridge means; and a frangible means engageable with said shoulder and the forward end of said projectile to form a sealing and securing connection between the projectile and barrel member operative to seal during initial travel of the projectile.

5. The combination with a barrel member and an explosive cartridge means, of a projectile mounted within the barrel member and co-actively associated with the cartridge means; and a frangible sealing and discharge delaying means connecting said projectile with the barrel member at their forward ends and operative to seal during initial movement of said projectile.

6. The combination with a barrel member having a sealing and retaining element at its forward or muzzle end and an explosive cartridge means, of a projectile mounted within the barrel member and co-actively associated with the cartridge means; a sealing and retaining element incorporated in said projectile at its forward end, and a frangible sealing and discharge delaying device fitting the sealing and retaining member elements of the barrel and projectile, said device being disposed so as to shear before discharge of the projectile and thereafter to form a pair of sealing rings operative during initial travel of said projectile.

MARCUS W. HAINES.
